UNITED STATES PATENT OFFICE

162,171

HARD SURFACED FLOOR COVERING

James Russell Jones, Jenkintown, Pa., assignor to Paulsboro Manufacturing Company, Fullerton,
Pa., a corporation of New Jersey

Application October 10, 1950, Serial No. 12,507

Term of patent 7 years

(Cl. D92—17)

To all whom it may concern:

Be it known that I, James Russell Jones, a citizen of the United States, resident of Jenkintown, in the county of Montgomery and State of Pennsylvania, have invented a new, original, and ornamental Design for Hard Surface Floor Covering, of which the following is a specification, reference being had to the accompanying drawing, forming a part thereof.

The figure is a face view of a hard surfaced floor covering showing my new design.

I claim:

The ornamental design for a hard surfaced floor covering, as shown.

JAMES RUSSELL JONES.
